US0D1016894S

(12) **United States Design Patent** (10) **Patent No.:** **US D1,016,894 S**
(45) **Date of Patent:** **** Mar. 5, 2024**

(54) **CAMERA MOUNT**

(71) Applicant: **GoPro, Inc.**, San Mateo, CA (US)

(72) Inventors: **Ryan Harrison**, Walpole, NH (US);
Ross Thayer, San Jose, CA (US);
Arthur Kwun, Newark, CA (US);
Mark Costa, Menlo Park, CA (US)

(73) Assignee: **GoPro, Inc.**, San Mateo, CA (US)

(**) Term: **15 Years**

(21) Appl. No.: **29/892,358**

(22) Filed: **May 17, 2023**

Related U.S. Application Data

(63) Continuation of application No. 29/767,750, filed on Jan. 25, 2021, now Pat. No. Des. 990,546, which is a continuation of application No. 29/726,067, filed on Feb. 28, 2020, now Pat. No. Des. 908,780, which is a continuation of application No. 29/699,948, filed on Jul. 30, 2019, now Pat. No. Des. 880,571, which is a continuation of application No. 29/665,322, filed on Oct. 2, 2018, now Pat. No. Des. 861,770, which is a continuation of application No. 29/610,474, filed on Jul. 12, 2017, now Pat. No. Des. 829,809, which is a continuation of application No. 29/561,955, filed on Apr. 21, 2016, now Pat. No. Des. 800,205, which is a continuation of application No. 29/525,956, filed on May 5, 2015, now Pat. No. Des. 757,842.

(57) **CLAIM**

The ornamental design for a camera mount, as shown and described.

DESCRIPTION

FIG. 1 is a front, top, and right-side perspective view of a camera mount;

FIG. 2 is a front elevational view thereof;

FIG. 3 is a rear elevational view thereof;

FIG. 4 is a left side elevational view thereof;

FIG. 5 is a right-side elevational view thereof; and,

FIG. 6 is a top plan view thereof.

The broken lines of equal length (i.e., dash-dash) in the drawings are included for the purpose of illustrating environmental structure and form no part of the claimed design.

1 Claim, 6 Drawing Sheets
